UNITED STATES PATENT OFFICE.

JOHN HENRY HOWARTH, OF LANETT, ALABAMA, ASSIGNOR TO WEST POINT MANUFACTURING CO., OF LANGDALE, ALABAMA, A CORPORATION OF ALABAMA.

LOOM.

Application filed December 30, 1924. Serial No. 758,821.

To all whom it may concern:

Be it known that JOHN HENRY HOWARTH, a citizen of the United States, residing at Lanett, in the county of Chambers and State of Alabama, has invented new and useful Improvements in Looms, of which the following is a specification.

The present invention relates to looms, and more particularly to looms for weaving fabric having two series of tubular sections, the two series being divided by a longitudinal section of different weave, and the individual sections of each series being connected by transverse strips of fabric of a different weave, for the production of bags. Each section of each series constitutes the body of a bag, the bottom of which is formed by the intervening strip between the two series, and the sides being formed by the transverse strips intervening between the individual sections.

The side edges of the fabric are left open to form the bag mouths and the separating cuts may be made through the center of the longitudinal central strip between the two series of sections and through the transverse strips between each tubular section.

Looms of this general character are known as "bag looms" and are well known in the art, the type of loom being illustrated in the patent to Michael, 953,632, Mar. 29, 1910. Such looms, however, are adapted to weave only a single series of tubular bag sections, united by transverse strips of different weave which form the bag bottoms. The present invention is an improvement upon such looms as are shown in the patent referred to, in that it materially increases the capacity of the loom by enabling the production in one weaving operation of two series of tubular bag sections.

An object of the invention is to provide for the weaving of double series, an ordinary "bag loom" as distinguished from a loom provided with a dobby or jacquard with which may be produced a similar fabric.

A further object of the invention is to provide in a bag loom improved means which is simple and positive in operation for automatically and quickly controlling the harness operating mechanism or cams so that the transverse or bag side strips may be regularly formed in proper width.

The above and other objects of the inven-

tion will become clear as the description proceeds in connection with the accompanying drawings, wherein one embodiment is illustrated. In these drawings:

Figure 1 is a left side elevation of a portion of the loom.

Figure 2 is a partial plan with some of the parts in section.

Figure 3 is a cross sectional view of one of the harness treadles, showing the means thereon for engaging the change cam.

Figure 4 is a diagrammatic view illustrating the weave, taken substantially on the line 4—4 of Figure 5.

Figure 5 is a diagrammatic view of the fabric formed by the loom.

Figure 6 is a diagrammatic longitudinal section on the line 6—6 of Figure 5, and

Figure 7 is a diagrammatic transverse section on the line 7—7 of Figure 5.

Looms of this character are ordinarily provided with a single set of four harnesses, which, by means of suitable cam connections, are given a 3 up, 1 down and 1 up, 3 down motion to form the tubular fabric, and an auxiliary cam is thrown into operation at the proper time to change the regular sequence or cycle of the harness movement and effect weaving of the transverse fabric strips which separate the tubular bag sections. In such looms, the side edges of the tubular fabric are ordinarily closed to form the bag sides.

With the loom of the present application, however, the bag sides are formed by the transverse strips and the edges of the fabric in the tubular sections are left open to form the bag mouths. The bottoms of the bags are defined by a longitudinal strip which separates the two series of tubular bag sections.

For this purpose, the loom is provided with two independent sets of harness, arranged side by side, and operated by independent mechanism, preferably two series of cams. Each set of cams includes a change cam to effect the weaving of the transverse strips which separate the bag sections of each series. The weaving of the longitudinal central strip which separates the two series of bag sections and forms the bag bottoms is caused by proper movement of the harnesses from the cams to form the shed.

In the operation of the loom, it is desirable to shift the two change cams simulta-

neously, in order that the transverse or dividing strips in the two series of bag sections will be aligned. For this purpose, a common cam shifting mechanism is utilized, 5 and the same preferably comprises, broadly, a device or chain having a pattern surface and given a step by step movement during operation of the loom, preferably by the lay. Shifting mechanism is adapted to engage 10 the pattern surface, and at predetermined points in the movement thereof is actuated to shift the change cams for the two sets of harnesses.

Referring to Figures 5, 6 and 7, there is 15 shown the bag fabric which the loom is adapted to produce. The same comprises two longitudinal series of tubular bag sections divided by a central strip 10, which forms the bag bottoms. The edges of the 20 fabric are open, as indicated at 11 (Figure 7), and the individual sections of each series are separated by transverse strips 12 of different weave, these strips forming the 25 sides of the bags. The two series of bag sections may be separated through the center of the strip 10 after the weaving operation and while the fabric is still in the loom, by suitable cutting mechanism, and the individual bag sections of each series may be 30 separated by cutting centrally through the transverse strips 12.

Referring now to the mechanism for weaving this fabric, there is illustrated in 35 the drawings as much of the loom mechanism as constitutes a departure from bag looms heretofore known. To illustrate the application of the novel mechanism of this type of loom, there is conventionally shown a loom side frame 13, in which is mounted 40 the rock shaft 14 carrying the lay 15 including its sword 16. The harnesses are arranged side by side in two sets of four harnesses each. Harnesses 17, 18, 19 and 20 constitute one set, and the other set is indicated by the reference characters 17', 18', 45 19' and 20'. The two sets of harnesses are slightly spaced apart, as indicated in Figure 2, and are actuated through connecting straps 21 and treadles 22, 23, 24 and 25 ful- 50 crumed at 26 upon the loom frame and engaged by suitable cams. A jack shaft 27, which may be driven through a gear 28 in any suitable manner from the loom drive shaft, carries a series of cams 29, 30, 31 and 55 32, which serve to actuate treadles for the harnesses 17, 18, 19 and 20, and impart thereto the normal cycle of operations. The series includes a change cam 33 slidably longitudinally of the jack shaft 27 carried by 60 frame bars 13, and having a pin 34 adapted to fit into an opening 35 in the cam 32, so as to rotate therewith. This change cam, it will be understood, is normally in the position shown in Figure 3, but when the trans- 65 verse strips 12 of the fabric are to be woven

it is shifted, by mechanism later to be described, into locking engagement with the cam 32 in order to change the normal cycle of operation of the harnesses from the 3 and 1 movement to a 2 up and 2 down movement, thus breaking up the tubular or bag weave and making a plain weave. The change cam 33 when interlocked with the cam 32 for rotation therewith engages a raised portion 36 (Figure 3) laterally offset from and carried by the treadle 25, the treadle having a roller 25' (Figure 3) for engagement with the cam 32.

It is thought that no further description of this detail is necessary since the construction is fully described in the patent to Michael, above referred to.

A second jack shaft 37 is mounted upon the frame bars 13, and is driven in unison with the shaft 37 through gear 38 from the loom drive shaft by mechanism (not shown). The jack shaft 37 carries a series of cams 39, 40, 41 and 42, which impart to the harnesses 17', 18', 19' and 20' their normal cycle of operation, which is the 3 and 1 movement. A change cam 43 has a pin 44 adapted to fit into a socket 45 in the cam 42, so that the change cam may be interlocked therewith when shifted laterally to change the cycle of harness operation. It will be understood that the treadle 25 is formed, as shown in Figure 3, in the same manner as treadle 25 of the other harness series, for engagement with the change cam 43.

The two change cams are intermittently operated simultaneously, and the mechanism for moving them will now be described. Mounted upon the loom frame is a suitable device, such as the chain 46, the pattern surface of which is provided with raised portions 47. The chain traverses a loose pulley 48 mounted upon a stud 49 on the frame, and at its other end extends over an actuating sprocket wheel 50 positioned upon the shaft 51, which is mounted in a bracket 52 and carries upon the inside of the frame a ratchet wheel 53. The pattern device of chain 46 is given a step by step movement, preferably from the lay. For this purpose, a pawl 54 is loosely carried at the end of a pawl bar 55 mounted at its lower end upon the lay sword 16, adjacent the rock shaft 14. A collar 56 surrounds the sword and has an outwardly extending arm 57 which carries a pivot stud 58 for the pawl bar 55. The bar 55 adjacent its upper end has a guide slot 59, into which projects a guide pin 60 upon the frame, and it will be understood that as the lay moves, the bar 55 is actuated to impart to the ratchet wheel 53 a clockwise movement, as viewed in Figure 1, in the direction of the arrow. Counterclockwise movement is prevented by means of a trip 61 pivoted upon the frame and in engagement with the ratchet wheel. As the

chain is moved in the direction of the arrow (Figure 1), the pattern projections 47 thereon are carried past a laterally projecting arm 63 on a depending lever 64, which is freely fulcrumed on the outer end of the ratchet wheel shaft 51. When the projections 47 engage the arm 63, they tend to move the lever to the left, as viewed in Figure 1, and retain the same in such position until all of the projections have travelled past the arm 63. Such movement of the lever serves to shift the change cams to operative position through a connecting rod 65, which, at one end 66, is forked and connected to the lever 64. It will be noted that the series of openings 64' extends toward its fulcrum so that the throw imparted to the connecting rod 65 may be varied. The connecting rod is secured at 67 to a bell crank 68 mounted upon the frame and secured to a reciprocating rod 69, which has bearings 70 in the frame and carries forked shifting arms 71, extending laterally and engaging the change cam hubs 72. The reciprocating rod 69 is formed in two sections, which are yieldingly united by a spring 73, and the rod is normally held in the position shown in Figure 2 by means of a spring 74 abutting the bearing 70 at one end and a collar 75 at its other end, the collar being adjustable longitudinally of the rod 69 to vary the tension of the spring. The yielding connection 73 permits the parts to give, should the pins 34, 44 upon the change cams be slightly out of alignment with their respective sockets when the cams are first shifted by the pattern chain, and thus danger of breakage of any of the parts is avoided. It will be understood that the tension of the return spring 74 may be varied by adjustment of the collar 75 so that its resistance will be proportioned to that of spring 73 and it will not interfere with proper shifting of the change cams by causing the spring 73 to yield when the change cam pins and their sockets are properly aligned. It will be observed that the mechanism for shifting the cams acts simultaneously upon the change cams of both series, and is quick and positive in its operation. The spring 74 will immediately return the cams to inoperative position as soon as the pattern surface of the chain 46 permits the lever 64 to swing to the right.

In Figure 4 there is illustrated diagrammatically the weave of this fabric, this view being taken substantially on the line 4—4 of Figure 5.

Referring to the central dividing section 10, it will be noted that the same comprises two spaced parallel tape portions 76, which are closely woven. The inner threads 76' of each tape portion are slightly spaced from the remaining warps and also spaced apart to provide a relatively loose woven selvage

portion which may be cut at 77 between the warp 76' to separate the two series of bag sections. This selvage portion comprises relatively few warp threads and is caused, as will be understood, by the slight spacing of the harnesses forming the line 77 along which the fabric may be conveniently divided.

At each side of the central strip 10, the fabric is formed into upper and lower plies 78 and 79, and by following the course of the respective warp threads (Figure 4) it will be noted that the second pick and the fourth pick 80 remain in the lower and upper plies, respectively. The first pick 81 at opposite sides of the center strip 10 is in different plies and the third pick 82 crosses from one ply to the other on opposite sides of the strip 10. The first pick 81 crosses to the upper ply on the left hand side, although it is in the under ply on the right hand side. In the same way, the third pick which is positioned in the upper ply on the right hand side of the fabric (Figure 4) passes to the under ply on the left hand side. This crossing of the weave produces the fabric illustrated diagrammatically in Figures 5, 6 and 7.

It should be understood that no claim is made herein to the fabric, the same being covered by my copending divisional application Serial No. 27,827, filed May 4, 1925.

Obviously, numerous changes may be made in the structure illustrated and described without departing from the invention which is defined in the following claims:

I claim:

1. In a bag loom, shed forming means adapted to weave a unitary tubular fabric including two independent sets of harness-cams, two independent sets of harnesses spaced transversely of the loom and operated respectively by said sets of cams, and suitable means adapted to interrupt the weaving of tubular fabric and to cause the weaving of intervening sections of different weave.

2. In a bag loom, shed forming means adapted to weave a unitary tubular fabric including two independent sets of harness-cams, two independent sets of harnesses spaced transversely of the loom and operated respectively by said sets of cams, and shiftable means adapted to simultaneously interrupt the weaving of tubular fabric by each set of cams and harnesses and to cause the weaving of intervening sections of different weave.

3. In a bag loom, shed forming means adapted to weave a unitary tubular fabric including two independent sets of harness-cams spaced transversely of the loom, two sets of harnesses spaced transversely of the loom and operated independently by said sets of cams, and automatic means for periodically operating said sets of cams simulta-

neously to interrupt the weaving of tubular fabric and cause the weaving of intervening sections of different weave.

4. In a bag loom, shed forming means adapted to weave a unitary tubular fabric including two independent sets of harness-cams spaced transversely of the loom, two sets of harnesses aligned and spaced transversely of the loom and operated independently by said sets of cams, and automatic means for periodically operating said sets of cams simultaneously to interrupt the weaving of tubular fabric and cause the weaving of intervening sections of different weave.

5. In a bag loom, shed forming mechanism to effect the weaving of a unitary tubular fabric and intervening connecting sections of different weave including two independent sets of harnesses spaced transversely of the loom, two independent sets of harness-cams each including a change cam, and means for simultaneously shifting the change cam of each set into and out of operative position, said means comprising a rod extending across the loom, means for connecting the rod to the cams, a pattern chain driven step by step, said chain having a pattern surface, and means connected with said rod and engageable by said surface to shift the cams intermittently.

6. In a bag loom, shed forming mechanism to effect the weaving of a unitary tubular fabric and intervening connecting sections of different weave including two independent sets of harnesses spaced transversely of the loom, two independent sets of harness-cams each including a change cam, and means for simultaneously shifting the change cam of each set into and out of operative position, and means comprising a rod extending across the loom, means for connecting the rod to the cam, a pattern chain driven step by step from the lay, said chain having a pattern surface, and means connected with said rod and engageable by said surface to shift the cams intermittently.

7. In a bag loom, shed forming mechanism to effect the weaving of a unitary tubular fabric and intervening connecting sections of different weave including two independent sets of harnesses spaced transversely of the loom, two independent sets of harness-cams each including a change cam, and means for simultaneously shifting the change cam of each set into and out of operative position, and means comprising a chain on the loom frame having a pattern surface, a ratchet wheel operatively associated with said chain pawl, means actuated by the lay for rotating said ratchet wheel step by step, and means engaging the pattern surface and adapted to shift said cams.

8. In a bag loom, shed forming mechanism to effect weaving of a unitary tubular fabric

and intervening sections of different weave including a set of harnesses, a set of harness-cams including a change cam, and means for shifting the change cam into and out of operative position, said means comprising a pattern chain, a ratchet wheel operatively associated with said chain to drive the same, means to rotate said wheel step by step directly from the lay, and means engageable by said chain to shift the cam intermittently.

9. In a bag loom, shed forming mechanism to effect weaving of a unitary tubular fabric and intervening sections of different weave including a set of harnesses, a set of harness-cams including a change cam, and means for shifting the change cam into and out of operative position, said means comprising a pattern chain, a ratchet wheel operatively associated with said chain to drive the same, means to rotate said wheel step by step directly from the lay, means engageable by said chain to shift the cam intermittently, and yielding connections between said last mentioned means and said cam.

10. In a bag loom shed forming means adapted to weave a unitary tubular fabric including two independent sets of harnesses arranged side by side, and means for independently operating said sets including shiftable devices adapted to interrupt the weaving of tubular fabric and to cause the weaving of intervening sections of different weave.

11. In a bag loom, shed forming means adapted to weave a unitary fabric having tubular sections open at the edges of the fabric and arranged in two parallel series spaced by a longitudinal intervening portion of different weave, comprising two independent sets of harnesses, and two sets of cams for independently operating said harnesses, said two sets of cams being substantially duplicates.

12. In a bag loom, shed forming means adapted to weave a unitary fabric having tubular sections open at the edges of the fabric and arranged in two parallel series spaced by a longitudinal intervening portion of different weave, comprising two independent sets of harnesses, and two sets of cams for independently operating said harnesses, said two sets of cams being substantially duplicates and each including shiftable means adapted to interrupt the weaving of tubular fabric and to cause the weaving of transverse intervening sections of different weave.

13. In a bag loom, shed forming means adapted to weave a unitary fabric having tubular sections open at the fabric edges and arranged in two parallel series spaced by a longitudinal intervening portion of different weave, comprising two independent

sets of harnesses and means for operating said sets independently adapted to cause the sets to weave substantially duplicate bag sections side by side longitudinally of the 5 fabric.

14. In a bag loom, shed forming means adapted to weave a unitary fabric having tubular sections open at the fabric edges and arranged in two parallel series spaced 10 by a longitudinal intervening portion of different weave, comprising two independent

sets of harnesses, and means for operating said sets independently adapted to cause the sets to weave substantially duplicate bag sections side by side longitudinally of the 15 fabric, said means including devices adapted to interrupt the weaving of tubular fabric and to cause the weaving of intervening sections of different weave.

In testimony whereof I have hereunto set 20 my hand.

JOHN HENRY HOWARTH.
